UNITED STATES PATENT OFFICE.

PAUL BOURCART, OF PARIS, FRANCE.

APPARATUS FOR PRODUCING THE INWARD RUN OF THE CARRIAGE IN SELF-ACTING MULES.

1,120,895.

Specification of Letters Patent.

Patented Dec. 15, 1914.

Application filed April 10, 1914. Serial No. 830,864.

To all whom it may concern:

Be it known that I, PAUL BOURCART, a citizen of the Republic of Switzerland, residing at 54 Avenue de Saxe, Paris, France, have invented certain new and useful Improvements in Apparatus for Producing the Inward Run of the Carriage in Self-Acting Mules, of which the following is a specification.

10 The movement of the carriage in its inward run in self-acting mules is a varied movement, that is, the carriage starts from rest, then has a progressively accelerated speed, and then from the middle point of 15 its run the speed of the carriage diminishes gradually until it becomes *nil* at the end of its run. This movement has been produced hitherto by means of a shaft on which are fixed spiral grooved pulleys, known as 20 "scrolls" which wind on and unwind cables whose other ends are attached to the carriage. The scroll shaft has a constant motion during the whole of the time during 25 which it is in gear, and it is by winding the cables on varying diameters that the carriage receives the varying motion which it is required to have. With that arrangement the winding on of the cables takes place therefore during a part of said motion on 30 very small diameters which are sometimes less than four times the diameter of the cable. In these circumstances the cables wear away very soon and entail a high cost of upkeep and loss through stoppages of 35 the machine.

My invention has for its object to provide an apparatus in which those drawbacks are eliminated. To this end the variations of 40 the linear speed of the carriage instead of being produced by winding-on members of varying diameter fixed on the back shaft that is a shaft having a uniform speed, are produced according to this invention by winding-on members of a suitable constant 45 diameter fixed on a shaft whose speed is caused to vary as desired by means of suitable mechanism. The diameter of the winding-on member can therefore be made large enough to avoid all wear of the cables. The 50 shaft on which the winding-on member of constant diameter is fixed, may of course, be driven at varying speeds according to requirements by any suitable mechanism. In particular, there may be employed for this 55 purpose the very simple mechanism herein-

after described which can be readily adapted to existing mules.

Figure 1 is a side elevation of my improved apparatus, viewed from the back of the headstock, showing also the essential parts of the old constructions which may be retained. Fig. 2 is a plan to Fig. 1. Fig. 3 is a vertical cross section of the speed varying mechanism. Fig. 4 is a horizontal section of this mechanism.

65 The driving power is transmitted by means of a clutch 1 of the friction or other type mounted on a vertical shaft 2 located at the back of the headstock. These parts are found in existing machines. At the lower 70 end of the clutch there is located a bevel pinion 3 that drives a bevel gear 4. These gears, as well as the scroll shaft 5, are also found in existing machines.

6 are the scrolls which according to my 75 invention, have a constant diameter large enough to avoid all wear of the cable which draws the carriage and which is wound on said scrolls. However, whereas in existing machines the bevel wheel 4 is fixed on the 80 shaft 5, according to my invention the wheel 4 is loose on the shaft 5 and is connected to a pinion 7. This pinion 7 drives a gear 8 fixed on a shaft 9 mounted in bushings 10, 10 provided in the casing 11 of the apparatus. The shaft 9 also carries a radial slotted arm 12 in which works a slide block 13. In the center of this slide block there 85 engages the crank-pin 14 of the crank 15 of a shaft 16 mounted in a bushing 17 in 90 the casing 11. The other end of the shaft 16 carries a toothed wheel 18 driving a gear 19 fixed on the scroll shaft 5.

The shaft 5 carries in the usual manner a plurality of scrolls and a check scroll. The 95 spiral grooves of these scrolls have a constant diameter. The shaft 16 is offset relative to the shaft 9.

At each inward run of the carriage the shafts 9 and 16 make exactly one revolution, 100 the ratio of the gears 18 and 19 having been selected accordingly. But whereas the crank 15 has a fixed length, the leverage of the driving force varies owing to the displacement of the arm block 13 in the slide 12. 105 Consequently the rotational speed of the shaft 16 will vary according to the law of variation of the said leverage. The constant diameter of the scrolls 6, 6 and of the check scroll is equal to the maximum diameter of 110

the scrolls hitherto used, and the development of their helix is equal to the linear travel of the carriage. The number of revolutions of the shaft 5 being known, it is merely necessary to determine the ratio between the gears 18 and 19 so that it shall correspond to one revolution of the shaft 16. The casing 11 indorsing the arm 12 and the crank 15, protects these parts from dust, and may be fixed to the floor, or to the upright 20 of the headstock. It may comprise the bearing 21 that supports the shaft 5 and at the same time serves as an abutment for the bevel wheel 4.

15 The bearings 22 for the shaft 5 are fixed to the ends of the headstock.

The hereinbefore described mechanism has the advantage that it requires only the very slightest alteration in the construction 20 of self-acting mules. My invention however is not restricted to this particular mechanism.

What I claim is:

1. In apparatus for producing the inward run of the carriage in a self-acting mule, the combination of a scroll shaft, scrolls of a constant diameter fixed on said shaft, and

means for continuously and progressively varying the speed of said scroll shaft for producing the required gradually accelerated and slackened speed of travel of the carriage.

2. In apparatus for producing the inward run of the carriage in a self-acting mule, the combination of a scroll shaft, scrolls of a constant diameter fixed on said shaft, a crank shaft and a slotted arm shaft both parallel to said scroll shaft, and offset relative to each other, the crank on the said crank shaft engaging by means of its crank 40 pin with a slide block working in the slotted arm of the other shaft, a hollow shaft loosely mounted on said scroll shaft, gear wheels on said hollow shaft one gear wheel driving said slotted arm shaft, the latter transmitting its rotation through said crank shaft to said scroll shaft at a continuously and progressively varying speed.

In testimony whereof I have affixed my signature in presence of two witnesses.

PAUL BOURCART.
